CLAIM

The ornamental design for a CDMA based personal assistant, as shown and described.

DESCRIPTION

FIG. 1 is a bottom, front, and right-side perspective of a CDMA based personal assistant,

FIG. 2 is a bottom, rear and right side perspective view thereof;

FIG. 3 is a front elevational view thereof;

FIG. 4 is a top plan view thereof;

FIG. 5 is a bottom plan view thereof;

FIG. 6 is a right-side elevational view thereof;

FIG. 7 is a left-side elevational view thereof; and,

FIG. 8 is a rear elevational view thereof.

The broken line showings throughout the views are for illustrative purposes only and form no part of the claimed design.
